UNITED STATES PATENT OFFICE.

FREDERICK J. CLARK, OF BUFFALO, NEW YORK, ASSIGNOR TO EASTMAN MACHINE COMPANY, OF BUFFALO, NEW YORK.

CLOTH-CUTTING MACHINE.

1,133,839.

Specification of Letters Patent. Patented Mar. 30, 1915.

Application filed April 28, 1913. Serial No. 763,947.

To all whom it may concern:

Be it known that I, FREDERICK J. CLARK, a citizen of the United States, residing at Buffalo, in the county of Erie and State of New York, have invented a new and useful Improvement in Cloth-Cutting Machines, of which the following is a specification.

This invention relates to improvements in cloth cutting machines of both the reciprocating and the rotary knife type. In the former, as commonly constructed, there is suspended from the frame of the machine in advance of the knife a presser foot which is adapted to rest upon and travel along the cloth in advance of the knife and hold the cloth in place, while in the latter or rotary knife type, no presser foot is generally used, but a knife guard is required which is suspended from the frame of the machine in advance of the knife to prevent the hand of the operator from coming in contact with the knife. It is necessary that both the presser foot in the reciprocating knife machine and the knife guard in the rotary knife machine be adjustably mounted on the frame of the machine so that they can be raised and lowered to accommodate whatever thickness of cloth the machine is to cut.

This invention relates to the means which are employed for adjustably securing this knife preceding member, whether presser foot or knife guard, to the frame of the machine and for raising and lowering it thereon, and the object of this invention is to mount the knife guard or presser foot on the frame of the machine in such manner that it can be easily and quickly adjusted by the operator of the machine to accommodate any desired thickness of cloth and will automatically lock in such adjusted position so that the necessary adjustment can be readily made by the operator with one hand.

In the accompanying drawings: Figure 1 is a side elevation of a rotary knife cloth cutting machine provided with a knife guard embodying the invention. Fig. 2 is a side elevation, on an enlarged scale, of the knife guard and its adjusting means detached

from the machine, showing the side of the guard opposite to that shown in Fig. 1. 50 Fig. 3 is a fragmentary section thereof on line 3—3, Fig. 2. Fig. 4 is a fragmentary sectional elevation of the front of the machine on line 4—4, Fig. 1.

Like reference characters refer to like 55 parts in the several figures.

The invention is shown in the drawings as applied to the knife guard of a rotary knife machine of standard type which comprises a base plate A, a standard B secured 60 thereto and supporting the frame C, a rotary knife D and a motor E which is carried by the frame and is geared or otherwise operatively connected with the knife. In front of the machine is hung the usual electric lamp 65 F for lighting the pattern in front of the knife. All of these parts are common in rotary knife machines and may be of any suitable and desired construction.

G represents the knife guard which may 70 be of any suitable construction. The guard shown comprises a depending curved portion g which is adapted to move over the upper surface of the cloth and an upwardly extending portion g' in advance of the front 75 edge of the knife which cooperates with the lower portion g to form a guard for the front edge of the knife. The guard G is provided with an upright rod or bar g² which is slidably mounted on the frame of 80 the machine and can be moved up and down thereon for raising and lowering the knife guard, and this invention relates to the means which are employed for accomplishing this and which are constructed as follows: H represents a support or bracket which stands upright at the front of the machine and may be made integral therewith or may be secured to the frame C of the machine in any suitable manner. In the 85 construction shown, this bracket is separate from the frame of the machine and has upper and lower ears or extensions h and h' which are secured to the frame C by screws h² h³. This bracket is provided adjacent to 90 its upper and lower ends with suitable ways

or bearings I for the upright rod g^2 in which this rod is adapted to slide vertically, and these ways are closed by plates i which retain this rod in sliding engagement there-
5 with.

For moving the rod g^2 up and down in the ways I for raising and lowering the knife guard, the following construction is employed: The bracket H is provided with 10 a forwardly projecting arm K which terminates in a toothed segment k and on this arm intermediate of its ends is pivoted an adjusting lever L which is connected at its inner end by a pivoted link l to the rod g^2 and at its opposite or outer end is provided with a handle portion l' having a spring-actuated dog or latch l^2 which is adapted to engage the teeth of the segment k. The dog l^2 may be mounted on the adjusting lever in 15 any suitable manner. In the construction shown, the handle portion l' of this lever has a longitudinal slot l³ formed in one side thereof and in this slot the dog l^2 is pivoted, a spring l⁴ being interposed between the dog 20 and the back of the slot to hold the dog normally in its advanced tooth engaging position.

The operator of the machine by taking 25 hold of the handle of the adjusting lever and pressing the dog l^2 inwardly can easily release this dog from engagement with the teeth of the segment k and can then move this lever to adjust the knife guard to any desired position. Upon releasing the dog 30 l^2 , this dog will at once spring into engagement with the teeth of the segment k and thus automatically lock the adjusting lever with the knife guard, which is supported by it, against movement in its adjusted position. The operation of the adjusting lever 35 for raising and lowering the knife guard can be easily and quickly effected by one hand so that, if desired, the adjustment of the knife guard can be made by the operator while the machine is in operation.

The adjusting lever stands in front of the machine where it is out of the way and where it can be easily reached by the operator. This arrangement of the adjusting lever also enables the lever and supporting bracket to be readily secured to the frame of the machine without requiring any material changes in the shape or structure of the frame. The construction is therefore 45 adaptable to machines of standard types without necessitating alterations therein, and as stated above, is applicable equally as well to the presser foot of a reciprocating knife machine as to the knife guard of a rotary knife machine. The construction forms a simple and easily operated adjustable support for the knife preceding member, whether knife guard or presser foot. It is inexpensive and can be readily secured

to the frame of the machine and when in 65 place thereon will operate to automatically and positively lock the knife guard or presser foot in its various adjusted positions.

I claim as my invention:

1. In a cloth cutting machine, the combination with the frame of the machine, of a supporting bracket secured to said frame, an upright rod mounted to slide vertically in said bracket, a member carried by said rod and arranged in front of the knife of the machine, an adjusting lever pivoted on said bracket and connected at one end with said rod for raising and lowering said knife-preceding member, and means for locking said lever in its adjusted positions, substantially as set forth.

2. In a cloth cutting machine, the combination with the frame of the machine, of a supporting bracket secured to said frame at the front of the machine, an upright rod mounted to slide vertically in said bracket, a member carried by said rod and arranged in front of the knife of the machine, an arm extending forwardly from said bracket, an adjusting lever pivoted on said arm and connected at one end with said rod for raising and lowering said knife-preceding member, and means for locking said lever in its adjusted positions, substantially as set forth.

3. In a cloth cutting machine, the combination with the frame of the machine, of a supporting bracket secured to said frame at the front of the machine, an upright rod mounted to slide vertically in said bracket, a member carried by said rod and arranged in front of the knife of the machine, an arm extending forwardly from said bracket and terminating in a toothed segment, an adjusting lever pivoted to said arm intermediate of the ends of said arm and connected at one end with said rod for raising and lowering said knife-preceding member, and a spring pressed dog carried by said lever and adapted to engage said toothed segment for locking said lever in its adjusted positions, substantially as set forth.

4. In a cloth cutting machine, the combination with the frame of the machine, of an upright rod mounted to slide vertically on said frame and provided at its lower end with a member arranged in front of the knife, an adjusting lever pivotally mounted on said frame and connected at one end with said rod for raising and lowering said member, and means for locking said lever in any one of a plurality of adjusted operative positions, substantially as set forth.

5. In a cloth cutting machine, the combination with the frame of the machine, of an upright rod mounted to slide vertically on said frame at the front thereof and provided at its lower end with a knife guard arranged in front of the knife, an adjust-

ing lever pivotally mounted on said frame in advance of said rod and connected at one end with said rod for raising and lowering said knife guard, and means for locking said lever in any one of a plurality of adapted operative positions, substantially as set forth.

Witness my hand in the presence of two subscribing witnesses.

FREDERICK J. CLARK.

Copies of this patent may be obtained for five cents each, by addressing the "Commissioner of Patents, Washington, D. C."

It is hereby certified that in Letters Patent No. 1,133,839, granted March 30, 1915, upon the application of Frederick J. Clark, of Buffalo, New York, for an improvement in "Cloth-Cutting Machines," an error appears in the printed specification requiring correction as follows: Page 3, line 6, for the word "adapted" read *adjusted*; and that the said Letters Patent should be read with this correction therein that the same may conform to the record of the case in the Patent Office.

Signed and sealed this 4th day of May, A. D., 1915.
